UNITED STATES PATENT OFFICE.

JOSEPH H. CAMPBELL, OF NEW YORK, N. Y.

AMMONIA-VAPOR ENGINE.

SPECIFICATION forming part of Letters Patent No. 399,183, dated March 5, 1889.

Application filed December 30, 1887. Renewed July 24, 1888. Serial No. 280,919. (No model.)

To all whom it may concern:

Be it known that I, JOSEPH H. CAMPBELL, a citizen of the United States of America, residing at New York, in the county of New York and State of New York, have invented 5 certain new and useful Improvements in Ammonia-Vapor Engines, of which the following is a specification, reference being had therein to the accompanying drawing.

10 The object of my invention is to fully saturate the weak solution used for spraying the exhaust-vapor from the cylinder of the engine by subjecting such solution, together with the excess or unabsorbed vapor, to progressive 15 and continuous steps of absorption, and to disseminate the heat of absorption set free at each such step by means of cooling-fluid.

Further objects of my invention are to provide a simple apparatus for indicating low 20 water in the boiler; to provide proper appliances for drawing off any vapor or gas in excess of saturation of the spraying-fluid after 25 said fluid has been used for absorbing the exhaust-vapor, and enforcing final absorption by pressure; to provide appliances for purging 30 the apparatus of air that may have been drawn into it; to provide means for lubricating the cylinder and the valves of the steam-chest; to return the combined exhaust-vapor 35 and spraying-fluid to the boiler by means of a vapor-pump—viz., a pump driven by the vapor of ammonia—which pump is similar in construction to an ordinary steam-pump used for like purposes; to control or neutralize, automatically or otherwise, any excess of pressure 40 that may occur in the boiler without being compelled to discharge or waste any of the ammonia contained within it, and to prevent any impurities—such as scale, &c.—from passing from the boiler to a jet used for spraying or absorbing the exhaust-vapor of the engine.

The foregoing and other novel and important features of my invention will be fully described hereinafter, and pointed out in the 45 claims.

In the drawing I have shown in a longitudinal vertical view, partly in section, an apparatus embodying the various features of my invention.

50 A represents a boiler having a vapor-dome, C.

E is an engine-cylinder connected with A and C by the vapor-pipe D.

l is the main cock or gate for shutting off steam.

55 O is the main exhaust-pipe for the engine, and J a pipe conveying fluid under boiler-pressure from the boiler to a spray or absorbing jet, j, in the exhaust-pipe O.

The weak ammonia solution, in order to 60 make it suitable for absorbing the exhaust-vapor, must be reduced in temperature to about 80° Fahrenheit. This is accomplished by passing the pipe J in the form of a coil through the shell T, through which cooling- 65 water is circulated, as explained hereinafter. In order to utilize part of the heat of which the spraying-fluid must be deprived, the pipe J may be passed through a heater, H, where 70 the weak solution within it is made to impart heat to the combined exhaust-vapor and spraying-fluid, which re-enter the boiler by means of the pipe F. The ammonia-vapor expelled by heat from the aqua-ammonia in the boiler, after acting upon the piston in cylinder E as 75 steam acts in the cylinder of a steam-engine, is upon being exhausted withdrawn by suction produced by the induced current created at j by the spray-fluid with which it is mixed, 80 absorption of a part of the exhaust-vapor thus taking place, and heat of absorption is evolved, as mentioned above. Such heat having a constant tendency toward defeating further and 85 complete absorption, I dispose of the same by passing the combined spraying-fluid and exhaust-vapor through the absorbers or surface-condensers S and S'. The absorber S is provided with a series of horizontal tubes, $n^1 n'$, $n^2 n^2$, and $n^3 n^3$, and with double heads K K', the spaces between said double heads being 90 divided by means of partitions b and g, so as to form the chambers 1, 2, 3, and 4.

The combined spraying-fluid and exhaust-vapor passes through the pipe O into the surface-condenser S and pipe O' on its way to 95 the absorber or surface-condenser S', which is of a construction similar to that of S, having horizontal tubes and double heads, the solution in S', however, being made to pass around the tubes while the cooling-water 100 passes through said tubes after having circulated through pipes $a' a^2 a^3$, shell T, and

pipe a^4 . Leaving the chambers and tubes of S' the cooling-water passes through the pipes a^5 and around the tubes in S , and is finally discharged through a^6 .

5 The completion of the absorption of the exhaust-vapor is accomplished gradually, as follows: The liquid and gas together pass from pipe O and chamber 1 in the surface-condenser S , through the pipes or tubes $n^1 n^2$, 10 into the chamber 2, where the liquid drops down to the bottom of said chamber to the pipes $n^3 n^4$ and absorbs the vapor which has accumulated in said chamber. By this act of absorption the solution is raised to a temperature 15 so high by the heat of absorption that it will absorb no more vapor, and is therefore returned through the cooling-tubes $n^2 n^3$, where its temperature is reduced and its capacity for absorption restored to the chamber 20 3, where it again falls through the vapor confined in the chamber and absorbs it. The heat of absorption again raises the temperature of the solution; but in passing through the tubes $n^3 n^4$ it is again cooled and, falling 25 through the vapor in the chamber 4, it absorbs an additional amount of vapor on its way toward the absorber S' , where further saturation takes place. By providing the absorber S with vertical chambers and horizontal 30 tubes and partitions the liquid contents of the absorber is rapidly removed by gravity, leaving the tubes and cooling-surfaces exposed to contact with the exhaust-vapor as it passes successively from one chamber to another, and, furthermore, any accumulation of 35 the exhaust-vapor at the entrance or top of the absorber is prevented.

It will be seen that the two absorbers S and S' might be consolidated in one frame or body 40 without changing their operations.

The solution after having absorbed a sufficient amount of the vapor to produce a partial vacuum in the cylinder by passing down through the primary absorber, S , and up 45 through the secondary absorber, S' , finds its way to the reservoir or well W , through the pipes $O^2 O^3 O^5$, or through pipe O^2 , pump P'' , and pipes O^4 and O^5 . On account of the velocity with which the solution is forced forward by 50 the force of the spray and the vacuum created by the absorption of the vapor and the action of the pumps a portion of the vapor adheres to the solution in excess of saturation at the temperature. This excess of vapor is released 55 as soon as the solution comes to a state of rest. To avoid back-pressure on the piston, which would result from the vapor being released, and which has been carried along by adhesion, the solution is caused to enter at 60 the bottom or lower part of the secondary absorber, S' , and to overflow from the top into the well W , which it enters at the bottom, or into pump P'' , as the case may be. As a consequence, the absorber S' is at all times 65 full of the solution, which is maintained at a sufficiently low temperature by means of the cooling-water passing through it, so that free

vapor released from the incoming solution may be absorbed therein.

P'' is a pump of any suitable kind, and constructed to pump either liquid or gases, or both, simultaneously. It is located between the absorber S' and well W , or may be placed instead between the chambers S and S' . Its office is to increase the vacuum in the cylinder by withdrawing the liquid and any free ammonia-gas from pipe O , and to produce a pressure in the receiving-well or in the secondary absorber and the well, thus assisting the engine and aiding absorption, as ammonia-gas will be more readily absorbed by water or by a weak solution when gas and liquid are under pressure.

I is a pipe leading from the reservoir or well W to the pump P , which pump draws the solution from the well and forces it back into the boiler through the pipe F , which forms a coil within the heater H . In this heater the spraying-fluid upon leaving the boiler surrounds said pipe F , transferring to its contents part 80 of its heat. The pipe I may enter the well W at about one-half its height, as shown, thus permitting the well to remain partially filled with the solution, in order that the gases or vapor carried along by adhesion may be dissolved in this solution. Furthermore, by having the well only partially filled with the solution a space is left in its upper portion for the reception of any air which may have been drawn into the apparatus. To remove such 85 air from the well W , to which the same would be carried with the solution passing through the absorbers, it would only be necessary to stop the operation of the feed-pump P by closing l^1 , so as to allow the solution to rise in said 90 well and to absorb any ammonia-vapor still remaining free, by directing into said well a quantity of cooled fluid withdrawn for such purpose from the spray-pipe J at any convenient point by means of the branch pipe L , 95 which is provided with a cock, l . Such pipe L may be passed through a cooling medium, or might be made to leave pipe J after the same has passed through the cooling-shell T .

By opening the cock l^2 after the ammonia-vapor in the well W has been absorbed the air remaining in the upper part of said well W will be expelled through the pipe M , the ammonia solution meantime filling the well W . After this is accomplished and cock l^2 110 has been closed the pump P may again be rendered operative by opening l^3 in order to reduce the solution in the well W to its former level. The pump P'' is principally intended 115 to reduce the amount of cooling-water needed, where it is difficult to obtain sufficient quantities of the same, by substituting compression in well W for the additional cooling-water otherwise required to complete absorption of the ammonia-vapor. When the engine is 120 running with only a partial load, the power for running pump P'' may be saved by disconnecting it and allowing the solution to pass from pipe o^2 into pipe o^3 , through pipe o^3 , v' 130

being a check-valve constructed to open toward pipe o^2 when the pressure in pipe o^2 equals or exceeds that in pipe o^3 . Instead of the check-valve v' an ordinary cock to be operated by hand might be substituted.

The reservoir or well W is connected with the main vapor-pipe by means of the pipe G, which serves in a measure to regulate the pressure in the plant and to dispose of small amounts of surplus vapor that may be developed beyond the requirements of the engine.

For such purpose it is provided with an automatic valve, v^2 , adjusted to open when dangerous pressure is reached in the boiler, thus affording means whereby the vapor can pass directly into the liquid in the well W. Surplus gas will thus be absorbed by the liquid, owing in part to the affinity which cool water or cool solution, not fully saturated, possesses for ammonia-gas, but owing principally to the great pressure under which said gas is thus discharged. To maintain the fluid in the well W cool for such purpose, I arrange to have cooling-water pass through coil a^2 , as mentioned heretofore.

I have found in practice that when ammonia-gas is introduced into a reservoir or well partly filled with absorbing liquid, as described, it is necessary, in order to obtain prompt absorption of said gas, to pass directly into the body of the liquid. If the gas were introduced above said liquid, the upper surface of the same, first coming in contact with said gas, would promptly develop heat of absorption, and a heated "liquid diaphragm" would soon be formed there, which would resist the downward passage and absorption of further amounts of gas.

The pipe J enters the boiler A at or below the low-water level, so that there is a constant flow of the solution under boiler-pressure from the boiler toward the spray-jet j in the exhaust-pipe O. The pipe J also acts as a safety appliance to the boiler in the following manner: When the solution in the boiler comes below the mouth of the pipe J, vapor instead of liquid will rush through said pipe and will be mingled with the exhaust-vapor from the cylinder. The excess of vapor at this point will cause a back-pressure on the piston of the cylinder which will check or stop the engine.

The cock l^4 in the pipe J may be used to regulate the amount of solution admitted to the exhaust-pipe through the jet j . J' is a pipe branching out from pipe J and leading to the interior of the cylinder; through it, upon opening cock l^4 , a spray of the weak solution is forced under boiler-pressure into the cylinder, for the purpose of lubricating the cylinder and valves of the steam-chest when starting and stopping the engine.

The feed-pump P is constructed similar to ordinary steam-pumps. It obtains its supply of vapor for propelling its piston from the main pipe D by means of the branch pipe d, in which cock l^5 serves to regulate the vapor-

supply. Its exhaust-pipe e leads into the main exhaust-pipe O at a point, x, located between the cylinder E and the absorber S. 70

P' is a double pump receiving its vapor supply for propelling it from the main pipe D by means of the branch pipe d', which contains the cock l^6 and automatic valve V³. Said pump is shown here to be provided with a central cylinder, c', which has a piston moving within. The exhaust-vapor is discharged through the exhaust-pipe f' into the main exhaust-pipe O at y, so as to be absorbed by the spray j, which performs the same function for 80 the vapor that passes through the engine-cylinder E. The piston-rod of the pump P' has attached to it a piston in the cylinder c' and another one in the cylinder c³.

a' is the suction-pipe for the cylinder c². 85 The pipe a' may take its supply from any suitable source of cooling-water. a⁰ is the discharge-pipe. The same enters the cooling-pipe a' a', which furnishes a constant supply of water, and is shown here to lead to the 90 well W.

h' is the suction-pipe for the cylinder C³, taking its supply from the liquid in the well W. It is provided with a cock, f.

h¹⁰ is the discharge-pipe, leading into the 95 vapor-space C of the boiler A.

The valve V³ is adjusted to open automatically when a given pressure is reached above it in the pipe d'.

Q is a pipe connecting the pipe O with the 100 pipe J.

V⁴ is a weighted valve opening automatically under a given pressure, the cock l⁸ being then open.

The operation of the pump P' is as follows: 105 Whenever there is an excess of pressure in the boiler and pipes D and d', the cock l⁶ being open, the weighted valve V³ will be opened and will admit vapor to c', thus starting the pump P'. The excess of pressure will also 110 open weighted valve v⁴, l⁸ being open at the time, thus permitting a larger supply of liquid to pass from the boiler to the absorbers, where it will be cooled and by gravity, or, forced by pump P'', will flow into the well W. The 115 cock l³ being closed the entire quantity of liquid thus drawn from the boiler and cooled will be withdrawn from the well W by means of pump P' and discharged through pipe h and spray-nozzle or rose-head n into the vapor-space of the boiler, where, being brought in contact with the vapor, it will absorb a portion of it, thus reducing the pressure. N N is a pipe connecting with the main vapor-pipe D, as well as with the exhaust-pipe O, and passing 125 around the engine-cylinder E. It is provided with a cock, l⁹, which the engineer may open at will, particularly when he shuts off the vapor by closing the throttle-valve l¹⁰. An automatic valve might, however, be substituted for 130 l⁹. When the engine is stopped suddenly, the pipe N N is to be principally employed. The pipe G, leading into the well W, discharges the gas into a comparatively strong solution,

(formed of combined spraying-fluid and exhaust-vapor,) and therefore will only be capable of taking care of ordinary and limited fluctuations in the pressure, while the pipe N N, 5 constructed to bring the vapor in direct contact with an induced current of weak solution at j , offers means of promptly relieving the boiler of excessive pressure.

The operation of the pump P is that of an 10 ordinary steam-pump, except that the exhaust of this pump is returned to the boiler by the aid of the spray-absorbing liquid used for the cylinder of the main engine, it being found in practice difficult to use an independent 15 spray for the pump without using an orifice or nozzle so large that the economy of the plant would be materially affected. The amount of vapor required for the work to be performed by pump P being small it is not 20 necessary to depend upon a spray-jet for the absorption of the exhaust-vapor, it being sufficient to bring it in contact with the fluid-exhaust in pipe O at X before entering the absorbers S and S'. For the purpose of obtaining 25 an increased supply of cooling-water for the fluid thus forced through the pipes J and O the water-cylinder c^2 of the pump P' is operated, as heretofore described, so as to add the water-supply passing through it, when the 30 pump P' is in motion, to the supply of cooling-water ordinarily passing through $a' a'$.

It will be seen that the fluid introduced into the vapor-space will be more effective in 35 promptly reducing the boiler-pressure, as it will come in direct contact with the vapor and will thus absorb it, while the fluid passed into the boiler through P below the fluid-line will only serve to reduce the general temperature of the boiler and of the fluid in the same 40 way.

As it may happen, when ammonia is first introduced into the boiler, that impurities—such as scale—be taken up by the spraying-fluid, it is desirable to prevent such impurities from reaching and obstructing the small 45 nozzle j , and for such purpose I provide in J the casing U, with strainer w , in such a manner that the strainer may be taken out and cleaned. For such purpose I form the 50 lower part of U as a detachable pocket, in which impurities may be temporarily received.

The cock l^1 will serve to shut off the water while U is being cleaned. It may also be used to regulate the amount of spraying-fluid which 55 it is desired to pass through said pipe J. When it is desired to draw fluid from the boiler B directly to the well W, the by-pass Z around the pump P may be used, which by-pass is provided with the cock l^3 .

60 I claim as new and desire to secure by Letters Patent—

1. In an aqua-ammonia engine, the combination, with the cylinder thereof, of a pipe carrying spraying or absorbing liquid from 65 the boiler to the exhaust-pipe, and a horizontal surface-condenser, substantially as set forth.

2. In an aqua-ammonia engine, the combination, with the cylinder thereof, of a pipe carrying spraying or absorbing liquid from 70 the boiler to the exhaust-pipe, a horizontal surface-condenser, and a secondary absorber into which the fluid enters below the liquid-line, substantially as set forth.

3. In an aqua-ammonia engine, the combination, with the cylinder thereof, of a pipe carrying spraying-fluid from the boiler to the exhaust-pipe and an absorber provided with vertical chambers and horizontal tubes, substantially as set forth. 75

4. In an aqua-ammonia engine, the combination, with the cylinder thereof, of a pipe carrying spraying-fluid from the boiler to the exhaust-pipe, and an absorber provided with vertical chambers and horizontal tubes and 85 partitions, and a secondary absorber into which the fluid passes underneath the liquid-line for the purpose of entrapping gas carried along by adhesion, substantially as set forth. 80

5. In an aqua-ammonia engine, the combination, with the boiler, of a reservoir containing liquid of greater absorptive power than that contained in the boiler, and a pipe provided with a valve constructed to admit automatically, in case of excessive pressure in 90 the boiler, vapor from the boiler into the liquid contained in the well, substantially as set forth. 95

6. In an aqua-ammonia engine, the combination, with the boiler, of a reservoir containing 100 solution of greater absorptive power than that contained in the boiler, a pipe with suitable valve leading from the vapor-space of the boiler into the liquid-space of the reservoir, and a pump for forcing the solution from 105 the reservoir back into the boiler, substantially as set forth.

7. In an aqua-ammonia engine, the combination, with the boiler, of a reservoir containing 110 solution of greater absorptive power than that contained in the boiler, and a pipe provided with a valve for admitting vapor from the boiler to the well, that part of said pipe within the fluid in the well being provided with a series of perforations, substantially as 115 set forth.

8. In an engine of the character described, the spray-pipe J, leading from the boiler to the exhaust-pipe of the cylinder, provided with the branch pipe J', leading into the cylinder, and having the cock l^4 , whereby a jet of the solution may be injected into the cylinder to lubricate the same prior to starting the engine, substantially as set forth. 120

9. In an engine of the character described, 125 the combination of an apparatus for re-absorbing the exhaust-vapor, and the pump P'', for increasing the vacuum on the piston and creating a pressure in the well, substantially as set forth.

10. In an engine of the character described, 130 the combination of an apparatus for re-absorbing the exhaust-vapor, the pump P'', placed between the absorbers and the well W,

and a by-pass around said pump with suitable valve, substantially as set forth.

11. In an engine of the character described, the combination, with the well W, partly filled 5 with aqua-ammonia for receiving the combined spraying-liquid and exhaust-vapor, of the pump P'', for discharging absorbing-liquid into said well, and the pipe M, with cock l², for purging the apparatus of air, substantially as specified.

12. In an engine of the character described, the combination, with the well W, of a pipe for filling said well with solution, the cock l³, for closing the outlet of said well, and the pipe 15 M, with cock l¹, for purging the apparatus of air, substantially as set forth.

13. In an engine of the character described, in combination with the boiler and the spray-pipe J, the strainer w, substantially as set forth.

14. In an engine of the character described, the combination, with the boiler and the spray-pipe J, of the casing U, with detachable bottom and containing the strainer w, substantially as set forth.

15. In an engine of the character described, the combination, with the boiler and the spray-pipe, of the strainer w and cock l¹¹, substantially as specified.

16. In an engine of the character described, the combination, with the boiler and the spray-pipe, of the cock l¹² in said spray-pipe, substantially as set forth.

17. In an aqua-ammonia engine, the combination, with a spray-pipe for conveying the fluid or solution from the boiler to the exhaust-pipe of the engine, of an additional pipe provided with a suitable valve or cock connecting the spray-pipe with the exhaust-pipe, whereby the amount of solution or fluid admitted from the boiler to the exhaust-pipe can be increased, as set forth.

18. In an aqua-ammonia engine, the combination of a pipe for conveying spraying-fluid from the boiler to the exhaust-pipe of the engine, an additional pipe provided with a suitable valve or cock connecting the spray-pipe with a cooling apparatus, and a pump for forcing the cooled fluid or solution into the vapor-space of the boiler, as set forth.

19. In an aqua-ammonia engine, the combination of a pipe for conveying spraying-fluid from the boiler to the exhaust-pipe of the engine, an additional pipe provided with a self-acting or automatic valve connecting the spray-pipe with the exhaust-pipe and cooling apparatus, and a pump for forcing the cooled

fluid or solution into the vapor-space of the boiler, as set forth.

20. In an aqua-ammonia engine, the combination of a pipe for conveying spraying-fluid from the boiler to the exhaust-pipe of the engine, an additional pipe provided with a self-acting or automatic valve connecting the spray-pipe with the exhaust-pipe and cooling apparatus, and a pump for forcing the cooled solution or fluid into the vapor-space of the boiler, said pump being arranged and adjusted to operate automatically under an increased pressure in the boiler, as set forth.

21. In an aqua-ammonia engine, the combination, with the boiler and engine-cylinder, of the pipe N N, provided with a cock or valve, for conveying vapor directly (and without passing it through the cylinder) to the 75 absorbing-jet j, discharging liquid under boiler-pressure for the purpose of relieving the boiler, substantially as specified.

22. In an aqua-ammonia engine, the combination of a boiler and pipe leading from the 80 vapor-space of the boiler to the cylinder of the engine, with a pump adapted to be operated by the vapor from the boiler, and a pipe leading from the exhaust of the pump to the exhaust-pipe of the engine, as set forth.

23. In an aqua-ammonia engine, a boiler for generating the vapor, and a pipe leading from the vapor-space of the boiler to the cylinder of the engine, a pump adapted to be operated by the vapor from the boiler, and a pipe leading from the exhaust of the pump to the exhaust-pipe of the engine, in combination with a spray of the cooled solution or fluid, whereby the exhaust from the cylinders of the pump and engine are absorbed, as set forth.

24. In an aqua-ammonia engine, the combination of the boiler, a system of circulating-pipes for conveying cooling-water to the absorbers, and a pump adjusted to automatically increase the amount of such cooling-water in 100 case of excessive pressure in the boiler, substantially as set forth.

25. In an aqua-ammonia engine, the combination, with the boiler and absorbers for absorbing the exhaust-vapor, of an air-pump, a receiving-well, and a feed-pump, said well being placed between said pumps, substantially as set forth.

In testimony whereof I affix my signature in presence of two witnesses.

JOSEPH H. CAMPBELL.
